UNITED STATES PATENT OFFICE.

EDWARD P. BAIRD, OF EVANSTON, ILLINOIS, ASSIGNOR TO WILLIAM T. BAIRD, OF NEW YORK, N. Y.

COUNTER.

1,143,021.

Specification of Letters Patent. Patented June 15, 1915.

Application filed August 14, 1912. Serial No. 714,955.

To all whom it may concern:

Be it known that I, EDWARD P. BAIRD, a resident of Evanston, in the county of Cook and State of Illinois, have invented certain new and useful Improvements in Counters, 5 of which the following is a full, clear, and exact description.

The invention relates to registering devices or counters and more particularly to the type or class adapted for use in connection with telephone service to count the number of calls or connections made for a subscriber's line or substation or the number of calls answered by an operator. In 10 this class of devices, it is desirable that the counters or registers shall be compact, so that a number of them may be conveniently arranged in associated relation with a switch-board and it is also desirable that some convenient and accurate means should be provided for restoring the counter to 15 zero, whenever desired. Furthermore, it is desirable to provide a construction, which can be produced at a low cost, since necessarily a large number of them are required 20 in a telephone exchange.

The invention consists in the several novel features hereinafter set forth and more particularly defined by claims at the conclusion 25 hereof.

In the drawings: Figure 1 is a perspective of a counter embodying the invention. Fig. 2 is a rear elevation, the back-plate of the case being removed. Fig. 3 is a section 30 taken on line 3—3 of Fig. 6, the case being omitted. Fig. 4 is a section taken on line 4—4 of Fig. 6, the case being omitted. Fig. 5 is a section taken on line 5—5 of Fig. 6, the case being omitted. Fig. 6 is a plan 35 view, the case and actuating lever being shown in section. Fig. 7 is an inverted plan, the case being shown in section. Fig. 8 is a transverse section on line 8—8 of Fig. 6. Fig. 9 is a transverse section taken on 40 line 9—9 of Fig. 6.

The improved counter is mounted in a suitable inclosing case a , which is usually mounted in a base a' so that the device may be set at any convenient point on a table 45 or shelf. The front of the case is provided with a sight-opening which is closed by a glass-plate 11, through which a dial 12 is visible. This dial is secured against a plate 18 and is provided with an outer annular 50 series 13 of marks for the indication of

units by a pointer 14, and an inner series of numerals or characters 15 for indicating a higher denomination, for example, hundreds, by a short pointer 16. The long pointer 14 is advanced step-by-step, once for 55 each tally and each rotation of said pointer causes the short pointer 16 to count one tally on the table 15.

The counting mechanism is mounted in a suitable frame which consists of a back-plate 17, a front-plate 18 and an intermediate plate 19. These plates are cross-connected by posts to form a rigid frame or mount for the several parts of the counting-mechanism. This frame is removably 60 held in the case by screws 21, which screw into posts 22 and extend through the removable back-wall a^2 of the case.

The mechanism for operating the counter step-by-step comprises an angular or bell-crank lever 23, which is pivoted as at 24 to the back plate 17 and has an arm 25 extending upwardly through an opening 26 in the top of the case and a finger-piece 27 at the upper end of said arm. This lever 70 also has a downwardly extending arm 28 which is connected to a spring 29 which retracts the lever to its normal position. A stop 30 limits the movement of said lever by 75 said spring. Each operation of said lever is 80 adapted to register one tally on the counter, by means of pawl 32 which is pivoted, as at 33, to lever 23 and is pressed by a spring 34 into engagement with a ratchet-wheel 35. Said ratchet-wheel is secured to 85 and rotates a pinion 36 which is mounted on an arbor 37 which is journaled in frame-plates 17 and 19. A detent 38 which is pivotally sustained at 39, is pressed into 90 engagement with ratchet 35 by a spring 39, 95 to hold said ratchet against backward rotation, and to prevent overthrow. Pinion 36 meshes with a gear-wheel 40, which has a hub 41 journaled in frame-plates 17, and a stud 42 having a sharp edge 43 projecting 100 beyond the front face of gear 40, is rigidly secured in said hub. Edge 43 is adapted to engage the face 44 of a disk 45 and to drive said disk by frictional contact. Disk 45 is secured to an arbor 51 (Fig. 8) which is 105 journaled in hub 41 and the unit indicator 14 is secured to said arbor. Resultantly, each operation of actuating-lever 23, will, by means of pawl 32, ratchet 35, pinion 36, gear 40, stud 42, disk 45 and arbor 51, ad-

110

vance indicator 14 one rotative step. Advance of the indicator 14 is effected during the retractile or spring-operated stroke of lever 23, and a shaft 62 in the frame prevents excessive throw of pawl 32, so that ratchet 35 will be advanced only one step for each operation of lever 23. Said stud 42 is normally held in engagement with face 44, by a resilient or spring strip 46, which has one of its ends affixed to frame-plate 17 by a screw 47 and presses against the outer end of hub 41 in which said stud is secured. The other end of said spring is free to be operated to release said hub, by a push-rod 48 which is slidably mounted in frame-plate 17 and the front of the case and has a groove adjacent its inner end which is adapted to receive a notched portion 49 of said spring, so that the spring may be pushed inwardly and away from hub 41 by said rod. A button 50 is secured to the outer end of push-rod 48 for convenience in operation.

For each rotation of indicator 14 the hundreds indicator 16 is advanced one step, that is, the count is carried to the hundreds indicator. This carrying is done by a gear-train comprising a pinion 56 secured to rotate with arbor 51 and meshing with a gear-wheel 57, a pinion 58 secured to gear 57 and a gear 59 which has a sleeve or hub 60 journaled in and extending through plate 18, and has the indicator 16 secured to its front end, adjacent the dial. Arbor 51 which operates the units indicator 14 extends through sleeve 60 and said indicator is secured to the front end thereof. By means of the carrying-mechanism, the hundreds indicator 16 will be advanced one rotative step for each complete rotation of the units indicator 14. A resetting device is provided and comprises a finger-wheel 61 on a shaft 62 which is journaled in frame-plates 17, 19, and a gear 63 on said shaft, which meshes with pinion 58 of the carrying-train. To restore the indicators to their normal or starting-point, button 50 will be pushed inwardly to operate spring 46 to release gear 40 and its stud 42 from frictional engagement with disk 44, and finger-wheel 61 will be rotated in one direction to rotate gear 63, pinion 58, gear 57, pinion 56, shaft 51 and indicator 14, to restore the latter indicator and will also rotate gear-wheel 59, which carries the hundreds indicator 16 to restore the latter to normal position. This rotation of these parts in resetting will be in direction which is reverse to the advancing movement imparted thereto by the lever 23.

60 A stop-device for arresting the indicators when they are both at the normal or starting point, consists of a lever 66, which is pivotally connected to one of the frame-plates at 67, has an arm 68, which has a terminal 69 adapted to enter a notch 70 in a

disk 71, which is secured on the resetting shaft 62, and said lever has another arm 72, which is adapted to pass into the path of a lug 73 on disk 44 which is on the arbor 51 which carries the units indicator. Shaft 70 62 being geared to pinion 58 of the gear-train which carries the tallies from arbor 51 of the units indicator, to the gear-wheel 59, which operates the hundreds indicator, will be rotated in synchronism with the hundreds indicator. Notch 70 in disk 71 is disposed so that when the hundreds indicator is in its normal position, the terminal 69 of detent 66 will pass into said notch, as shown in Fig. 4, and lever-arm 72 will then be disposed in the path of lug 73 to arrest the units indicator and arbor 51 at the starting or zero point. A spring 74 acts on lever 66 to press, and yieldingly hold, the lever in operative relation to disks 71 and 44. Resultantly, when arbor 51 is turned by the gear-train between it and shaft 62, detent-terminal 69 will ride on the concentric peripheral portion of disk 71 until the hundreds indicator reaches its normal position or starting point, when terminal 69 will pass into notch 70 and cause arm 72 to be moved into the path of lug 73 to arrest the units indicator at the starting point. Arm 72 is disposed so that stop 73 will move it out of the way during the advancing movements of indicator 14 and arbor 51, until the multiple indicator 16 has been advanced sufficiently to cause disk 71 to hold said lever arm 72 clear of stop 73. During the resetting operation, however, the lever arm 72 passes into operative position to arrest stop 73 against reverse and excessive rotation of arbor 51.

The invention thus provides an improved counter or register which is simple in construction and which can be readily reset when desired.

The invention is not to be understood as restricted to the details set forth, since these may be modified by the skilled mechanic within the scope of the appended claims without departing from the spirit and scope of the invention.

Having thus described the invention what I claim as new and desire to secure by Letters Patent is:

1. In a counter, the combination with indicators for different denominations, mechanism for operating the same, and carrying mechanism between said indicators, of resetting mechanism, a stop lever mounted to arrest the indicator for the lower denomination at zero, and means for rendering the stop lever operative when the indicator for the other denomination reaches zero.

2. In a counter, the combination of rotatable indicators for different denominations, gear mechanism for operating the indicators, a lever for operating the gear

mechanism step by step, resetting mechanism, a stop rotating with the indicator for the lower denomination, a stop lever mounted to arrest the indicator for the lower 5 denomination at zero, and a disk for rendering the stop lever operative when the indicator for the other denomination reaches zero.

3. In a counter, the combination of rotatable indicators for different denominations, gear mechanism for operating the indicators, a lever for operating the gear mechanism step by step, resetting mechanism, a disk secured to rotate with the indicator for the lower denomination and having 10 a one-way stop thereon, a stop lever having an arm mounted to engage said stop when the indicator for the lower denomination is at zero, and means for rendering the 5

stop lever operative when the indicator for the higher denomination is at zero. 20

4. In a counter, the combination with rotatable indicators for different denominations, mechanism for operating the same, and carrying gears between the indicators, of resetting mechanism, a disk secured to 25 rotate with the indicator for the lower denomination and having a one-way stop thereon, a lever mounted to engage said stop when the indicator for the lower denomination is at zero, and a notched disk for rendering the lever operative when the indicator for the other denomination reaches zero. 30
